(57) **CLAIM**

The ornamental design for a trim for light fixture, as shown and described.

DESCRIPTION

This application is related to commonly assigned, application Ser. No. 29,281,131, and to application Ser. No. 29/221,202, and application Ser. No. 29/221,314.

FIG. 1 is a front elevation view of the trim for light fixture of the present invention;

FIG. 2 is a right side elevation view thereof;

FIG. 3 is a left side elevation view thereof;

FIG. 4 is a top plan view thereof;

FIG. 5 is a bottom plan view thereof; and,

FIG. 6 is a view identical to FIG. 1, with the broken line ornaments removed for enhanced clarity.

The surface of the facets are included in the claimed design but the edges where the facets change plane are shown in broken line because they form no part of the claim design.

The broken line showing is for illustrative purposes only and forms no part of the claimed invention.
